DESIGN FOR A COMBINED PENCIL AND ADVERTISING PANEL

Joseph G. Lipic, Jr., St. Louis, Mo., assignor to
Jos. Lipic Pen Co., St. Louis, Mo., a corporation
of Missouri

Application December 28, 1944, Serial No. 117,124

Term of patent 14 years

(Cl. D74—24)

To all whom it may concern:

Be it known that I, Joseph G. Lipic, Jr., a citizen of the United States of America, residing in the city of St. Louis, State of Missouri, have invented a new, original, and ornamental Design for a Combined Pencil and Advertising Panel, of which the following is a specification, reference being had to the accompanying drawing, forming a part thereof.

Fig. 1 is a front elevational view of a combined

pencil and advertising panel showing my new design; and

Fig. 2 is a side elevational view of the same.

The design is characterized by providing a pencil with a panel at the top thereof on which advertising matter may be displayed.

I claim:

The ornamental design for a combined pencil and advertising panel, as shown and described.
